(57) **CLAIM**

The ornamental design for a weight enclosure for an exercise machine, as shown and described.

DESCRIPTION

FIG. 1 is a front elevation view of the weight enclosure for an exercise machine of the present invention.

FIG. 2 is a right side elevation view of the weight enclosure for an exercise machine of the present invention.

FIG. 3 is a rear elevation view of the weight enclosure for an exercise machine of the present invention.

FIG. 4 is a left side elevation view of the weight enclosure for an exercise machine of the present invention.

FIG. 5 is a top plan view of the weight enclosure for an exercise machine of the present invention.

FIG. 6 is a bottom plan view of the weight enclosure for an exercise machine of the present invention.

FIG. 7 is a front perspective view of the weight enclosure for an exercise machine of the present invention.

FIG. 8 is a front side perspective view of the weight enclosure for an exercise machine of the present invention; and,

FIG. 9 is a rear side perspective view of the weight enclosure for an exercise machine of the present invention.
